Primary Examiner — T Chase Nelson*Assistant Examiner* — Rachel Wolfe(74) *Attorney, Agent, or Firm* — Bruce P. LaBrie;
Resolution Legal Group(57) **CLAIM**

The ornamental design for a LED light, as shown and described.

DESCRIPTION

FIG. 1 is a front elevational view of a LED light showing my new design;

FIG. 2 is a rear elevational view thereof;

FIG. 3 is a right elevational view thereof;

FIG. 4 is a left elevational view thereof;

FIG. 5 is a top view thereof;

FIG. 6 is a bottom view thereof;

FIG. 7 is a perspective thereof; and,

FIG. 8 is another perspective view thereof.

The structural features depicted by broken lines have been shown for the purpose of illustrating portions of the LED light that form no part of the claimed design.

1 Claim, 4 Drawing Sheets(56)
